UNITED STATES PATENT OFFICE.

JOHN H. HOLDEN, OF PEKIN, NORTH DAKOTA.

COMPOUND TOOL.

1,079,243.

Specification of Letters Patent.

Patented Nov. 18, 1913.

Application filed May 6, 1913. Serial No. 765,955.

To all whom it may concern:

Be it known that I, JOHN H. HOLDEN, a citizen of the United States, residing at Pekin, in the county of Nelson and State 5 of North Dakota, have invented certain new and useful Improvements in Compound Tools, of which the following is a specification.

The present invention relates to improvements in implements or tools, particularly adapted for preparing belts for being laced or coupled, the object in view being to provide a compound tool embodying all those elements in coöperative relation which are 15 necessary for accomplishing the above mentioned purpose.

To this end the tool consists of a pair of complementary members adapted to form a piercing element constituting a scratch- 20 awl when in closed position, one of the members being internally grooved so as to form cutting edges whereby a hole formed by the piercing element may be properly enlarged, locking means being provided for 25 maintaining the members in the closed position aforesaid when the device is performing its piercing function and operable to release the members to thereby permit use 30 of the cutting edges aforesaid, said locking means just mentioned consisting of a lace cutting element and gage.

A still further object of my invention is to provide a wire cutting element on the contiguous edge portions of the members 35 forming the tool, and with the above and other objects in view this invention consists of the construction, combination, and arrangement of parts, all as hereinafter more fully described, claimed, and illustrated in 40 the accompanying drawings, wherein:

Figure 1 is a perspective view of the embodiment of my invention. Fig. 2 is a longitudinal sectional view. Fig. 3 is a longitudinal sectional view of the tool taken 45 about on the plane indicated by the line 3—3 of Fig. 2. Fig. 4 is a transverse sectional view on the line 4—4 of Fig. 3. Fig. 5 is a similar sectional view on the line 5—5 of Fig. 3. Fig. 6 is a perspective view of 50 the lace cutting element alone.

Through the following detail description, and on the several figures of the drawing, similar parts are referred to by like reference characters.

55 A tool constructed in accordance with my invention comprises a pair of complementary

members 1 and 2 which are connected intermediate their ends by means of the pivot 3, said members forming when closed a piercing element 4 at one end, while at the other end the two members or sections constitute a handle 4'. It will be observed that the piercing element 4 tapers to a sharp point and the tool being constructed preferably of metal the element 4 constitutes a scratch awl designed to be employed in the well known manner of an article of this nature for marking upon metal, leather, wood or the like. One of the complementary members aforesaid is longitudinally grooved, 70 as designated by the numeral 5, on its inner surface adjacent the other member, the grooving of this member forming at each side of the same cutting edges 6, said cutting edges extending substantially the full 75 length of the groove member.

It is obvious that the groove 5 may be formed in either one of the two members but as illustrated in the drawings section 2 of the tool is thus formed and from one 80 side of the tool is formed a transverse groove 7 located adjacent the point of pivotal connection in each of the members 1 and 2, said groove extending approximately to the opposite side of the tool. In this 85 manner a wire cutting element 8 is formed at one side of the tool while the groove 7 permits the insertion of the wire between the members in an obvious manner.

Describing the use of my invention as 90 particularly adapted in preparing a belt for being laced together at its adjacent ends to make it continuous, the piercing element 4 is first inserted at the proper point so as to perforate the belt (not shown). When 95 an opening has been made it is contemplated that the members 1 and 2 will be separated by moving them pivotally on the pivot 3 and the member 2 is then inserted in the opening just mentioned and subsequently turned, the cutting edges of said member properly rounding the hole the size of which is governed by the extent to which the member 2 is inserted therein.

It is desirable that locking means be employed to hold the members 1 and 2 in closed position whereby the piercing element 4 may be properly used either as an awl or for initial piercing as just described, and hence one of the sections or members, 110 preferably the one designated 2 is provided with a longitudinal groove 9 on the inner
